DESIGN FOR A COMBINATION DESK UNIT

Emanuel R. Posnack, New York, N. Y.

Application January 4, 1940, Serial No. 89,305

Term of patent 14 years

To all whom it may concern:

Be it known that I, Emanuel R. Posnack, a citizen of the United States, resident of the Borough of Queens, in the county of Queens and city and State of New York, have invented a new, original, and ornamental Design for a Combination Desk Unit, of which the following is a specification, reference being had to the accompanying drawing, forming part thereof.

The figure is a perspective view of the combination desk unit showing my new design, the essential features of which are disclosed in full lines.

I claim:

The ornamental design for a combination desk unit, substantially as shown and described.

EMANUEL R. POSNACK.
